US00D624472S

(12) **United States Design Patent**
Schmitz et al.

(10) **Patent No.:** US D624,472 S
(45) **Date of Patent:** ** Sep. 28, 2010

(54) **INNER SIDE PORTION OF A BRAKE ROTOR**

(75) Inventors: **Johann Schmitz**, Wurmlingen (DE);
Ingo Hoffmann, Tuttlingen (DE);
Manfred Pallenien, Engen (DE)

(73) Assignee: **Schwäbische Hüttenwerke Automotive GmbH & Co. KG** (DE)

(**) Term: **14 Years**

(21) Appl. No.: **29/306,267**

(22) Filed: **Apr. 4, 2008**

(30) **Foreign Application Priority Data**

Oct. 4, 2007 (DE) 407 04 958

(51) **LOC (9) Cl.** 12-16

(52) **U.S. Cl.** D12/180

(57) **CLAIM**

The ornamental design of an inner side portion of a brake rotor, as shown and described.

DESCRIPTION

FIG. 1 is a first perspective view of an embodiment thereof as viewed from a generally front-elevational perspective, and, FIG. 2 is a second perspective view thereof.

In the drawings, the broken lines represent environmental portions of the structure and form no part of the claim.
